WALKING ATTACHMENT FOR DOLLS, &c.

1,370,721.

Specification of Letters Patent.

Patented Mar. 8, 1921.

Application filed July 27, 1920. Serial No. 399,312.

To all whom it may concern:

Be it known that I, DAVID ZAIDEN, a citizen of Russia, residing at East Orange, in the county of Essex and State of New Jersey, have invented certain new and useful Improvements in Walking Attachments for Dolls, &c.; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to toys, such as dolls, toy animals, and the like; and the invention has reference, more particularly, to an improved means for connecting the legs of such toys to the body thereof whereby the toy may be so manipulated as to cause the legs to simulate the motions of walking.

The invention has for its principal object to provide a novel construction of connecting attachment for securing the legs to the body of a toy, such as a doll, so that the legs may be caused to simulate the motions of walking; and to this end the present invention provides a novel construction of leg joint which may be either built into new dolls or which may be utilized as attachments to convert old dolls into walking dolls.

Other objects of the present invention, not at this time more particularly enumerated, will be clearly understood from the following detailed description of the same.

With the various objects of the present invention in view, the same consists, primarily, in the novel construction of walking attachment for dolls and similar toys hereinafter set forth; and, furthermore, the invention consists in the novel arrangements and combinations of the various parts, as well as in the details of the construction thereof, all of which will be hereinafter more fully described and claimed.

The invention is clearly illustrated in the accompanying drawings, in which:—

Figure 1 is a front view of a doll provided with the novel walking attachments made according to and embodying the

principles of my present invention; Figs. 2 and 3 are side elevations of the doll (the upper portion of the body being broken away), the same illustrating the operations of the novel attachments as the legs are caused to make successive stepping movements in simulation of walking; Fig. 4 is a detail face view of one of my novel walking attachments removed from the doll, the same being drawn on an enlarged scale; and Fig. 5 is a horizontal section, taken on line 5—5 in said Fig. 4.

Similar characters of reference are employed in all of the above-described views, to indicate corresponding parts.

Referring now to said drawings, the reference character 1 indicates a doll, and 2 indicates the trunk or body-portion thereof. Connected with the shoulder portions of said body-portion 2 are shoulder brackets 3, provided at their free ends with downwardly extending integral portions 4 providing stationary upper arm parts parallel to and outwardly off-set from the sides of the body-portion 2. Pivotedly connected with the lower extremities of said upper arm parts 4 are fore-arm portions 5. The reference characters 6 and 7 indicate the respective leg-portions of the doll.

My novel walking attachments serve to interconnect said respective leg-portions 6 and 7 with the lower end of the body-portion 2. Each walking attachment comprises a stationary member 8 which is rigidly secured at its upper end, by means of fastening screws 9, or equivalent means, to one side of the lower end of the body-portion 2, and so that the free end of the same projects downwardly from said body-portion. Pivotedly connected with the lower free end of said stationary member 8 is a swinging or oscillatable member 10, to the lower end of which is secured by means of bolts 11 and 12, or other equivalent fastening means, one of the leg-portions of the doll. The meeting ends of said stationary member 8 and swinging or oscillatable member 10 are secured together in pivotal relation by means of a pivot bolt 13 passed through perforations or openings provided in said meeting ends for the reception of the same. Said stationary member 8 is provided in its body, above the point of pivotal connection with

said swinging or oscillatable member 10, with a cutaway portion or opening 14, the sides 15 and 16 of which provide stops adapted, at proper times, to be engaged by 5 a stop-lug 17, which is integrally connected with the upper end of said swinging or oscillatable member 10, and which is turned downwardly and inwardly so as to move laterally within the embrace of said opening 14. In like manner, said swinging or oscillatable member 10 is provided in its body, below the point of its pivotal connection with said stationary member 8, with a similar cutaway portion or opening 18, the 15 sides 19 and 20 of which provide stops adapted, at proper times, to be engaged by a stop-lug 21, which is integrally connected with the lower end of said stationary member 8, and which is turned upwardly and 20 outwardly so as to move laterally within the embrace of said opening 18.

Coiled about the pivot bolt 13 is a spring member 22, one leg 23 of which extends upwardly, the same having at its free end a 25 lateral portion or projection 24 arranged in stopped engagement with the side 16 of the opening 14 of said stationary member 8, and the other leg 25 of which extends downwardly, the same having its free end portion 26 engaged with the end of the bolt 12, whereby the tension of said spring member 30 normally causes the swinging or oscillatable member 10 to swing forwardly, and to thereby normally hold the leg connected therewith in a forwardly swung position, as determined by the engagement of the stop lug 17 with the side 15 of the opening 14 of the stationary member 8, and the simultaneous engagement of the side 19 of the opening 18 35 of the oscillatable member 10 with the stop-lug 21. A nut 27 engaged on the end of said pivot bolt 13, holds the spring member 22 against accidental displacement.

As will be understood from an inspection 45 of the drawings, one of the attachments, above described in detail, is provided for each leg-portion 6 and 7, to operatively connect the same for walking movements with the body portion 2 of the doll or the like.

50 The manner of manipulating the doll to cause, through the operation of said walking attachments, the respective leg-portions 6 and 7 to simulate successive stepping or walking movements, is as follows:

55 The child in playing with the doll, or other toy, places the same on the floor or other surface, and holds the same by grasping one of the fore-arm portions 5. By then slightly tipping the doll sidewise and outwardly, the leg 6 is slightly raised to clear the foot from the floor, and the weight of the doll is supported upon the leg 7. By then moving the doll forward, the oscillatable member 10 of said leg 7 will be caused 60 to swing rearward against the tension of its

spring member 22, thereby causing the said leg 7 to incline rearwardly, as shown in Fig. 2, while the oscillatable member 10 of the leg 6 is normally positioned to throw the latter forward, as shown in said Fig. 2. By then slightly tipping the doll sidewise and inwardly the leg 6 is brought down with its foot portion engaging the floor, and at the same time the leg 7 is slightly raised to cause its foot portion to clear the floor, 75 whereupon the additional stored tension of the spring member controlling the oscillatable member 10 of said leg 7 will cause the latter to swing forward into the next stepping position, as shown in Fig. 3 of the 80 drawings, while the forward movement of the doll body causes the oscillatable member 10 of the leg 6 to swing back with said leg and against the tension of its spring member. It will be apparent that successive stepping movements may be thus caused *ad libitum*, so that as the child walks along, the doll is likewise caused to simulate walking movements at the side of the child. It 85 will be understood that the respective stop-lugs 17 and 21, as alternately engaged with opposite sides of the openings 14 and 18, will serve to limit the swinging movements of the oscillatable members 10 and the leg-portions connected therewith, and thereby 90 tend to maintain the stepping movements equal and uniform.

I am aware that some changes may be made in the arrangement and combinations of the various devices and parts, as well as 100 in the details of the construction of the same, without departing from the scope of my present invention as set forth in the foregoing specification, and as defined in the appended claims. Hence, I do not limit my 105 invention to the exact arrangements and combinations of the various devices and parts as described in said specification, nor do I confine myself to the exact details of the construction of said parts as illustrated 110 in the accompanying drawings.

I claim:

1. The combination with the body and leg portions of a toy of walking attachments interconnecting said leg portions with the 115 body, each comprising a stationary member secured to the body, an oscillatable member secured to a leg portion, means pivotally connecting said oscillatable member with said stationary member, and spring means 120 normally swinging said oscillatable member in a forward direction while adapted to yield to rearward swinging movement of the same.

2. The combination with the body and leg portions of a toy of walking attachments interconnecting said leg portions with the body, each comprising a stationary member secured to the body, an oscillatable member secured to a leg portion, means pivotally connecting said oscillatable member with said 125 130

stationary member, spring means normally swinging said oscillatable member in a forward direction while adapted to yield to rearward swinging movement of the same, 5 and stop means for limiting the swinging movements of said oscillatable member in each direction.

3. The combination with the body and leg portions of a toy of walking attachments 10 interconnecting said leg portions with the body, each comprising a stationary member rigidly secured by one end to the body, an oscillatable member pivotally secured to the free end of said stationary member, the 15 lower end of said oscillatable member being rigidly secured in supporting relation to a leg portion, spring means interconnected between said stationary member and said oscillatable member to normally press the latter 20 in a forwardly swung position, and a stop device on said oscillatable member to co-operate with portions of said stationary member for limiting the movement of the former in each direction.

4. The combination with a toy having a body and leg portions of walking attachments interconnecting the latter with the former, each comprising a stationary member rigidly secured by one end to said body, 25 an oscillatable member rigidly secured by its lower end to a leg portion, a pivot means connecting together the free ends of said stationary member and said oscillatable member, a spring means coiled on said pivot 30 means, one arm of said spring means being engaged with said stationary member, and the other arm of said spring means being engaged with said oscillatable member, said spring means normally swinging said oscillatable member in a forward direction while 35 adapted to yield to rearward swinging movement of the same.

5. The combination with a toy having a body and leg portions of walking attachments interconnecting the latter with the former, each comprising a stationary member rigidly secured by its upper end to said body, an oscillatable member rigidly secured 40 by its lower end to a leg portion, a pivot means connecting together the free ends of said stationary member and said oscillatable member, a spring means coiled on said pivot 45 means, one arm of said spring means being engaged with said stationary member, and the other arm of said spring means being engaged with said oscillatable member, said spring means normally swinging said oscillatable member in a forward direction while adapted to yield to rearward swinging movement of the same, and stop means for 50 limiting the swinging movements of said oscillatable member in each direction.

6. The combination with a toy having a body and leg portions of walking attachments interconnecting the latter with the

former, each comprising a stationary member rigidly secured by its upper end to said body, an oscillatable member rigidly secured by its lower end to a leg portion, a pivot means connecting together the free ends of 70 said stationary member and said oscillatable member, a spring means coiled on said pivot means, one arm of said spring means being engaged with said stationary member, the other arm of said spring means being engaged with said oscillatable member, said spring means normally swinging said oscillatable member in a forward direction while adapted to yield to rearward swinging movement of the same, said stationary member having an opening in its body, and said oscillatable member having at its upper end an inwardly turned stop-lug projecting into 75 said opening to co-operate with the sides of the latter.

7. The combination with a toy having a body and leg portions of walking attachments interconnecting the latter with the former, each comprising a stationary member rigidly secured by its upper end to said 90 body, an oscillatable member rigidly secured by its lower end to a leg portion, a pivot means connecting together the free ends of said stationary member and said oscillatable member, a spring means coiled 95 on said pivot means, one arm of said spring means being engaged with said stationary member, the other arm of said spring means being engaged with said oscillatable member, said spring means normally swinging 100 said oscillatable member in a forward direction while adapted to yield to rearward swinging movement of the same, said stationary member having an opening in its body, said oscillatable member having at its 105 upper end an inwardly turned stop-lug projecting into said opening to co-operate with the sides of the latter, said oscillatable member likewise having an opening in its body, and said stationary member having at its 110 lower free end an inwardly turned stop-lug projecting into said latter opening to co-operate with the sides of the same.

8. The combination with a toy having a body and leg portions of walking attachments interconnecting the latter with the former, each comprising a stationary member rigidly secured by its upper end to said body, an oscillatable member rigidly secured by its lower end to a leg portion, a 115 pivot means connecting together the free ends of said stationary member and said oscillatable member, a spring means coiled on said pivot means, one arm of said spring means being engaged with said stationary member, the other end of said spring means 120 being engaged with said oscillatable member, said spring means normally swinging said oscillatable member in a forward direction while yielding to rearward swinging 125 movement of the same, and stop means for limiting the swinging movements of said oscillatable member in each direction.

movements of the same, said oscillatable member having an opening in its body, and said stationary member having at its lower free end an inwardly turned stop-lug projecting into said opening to coöperate with the sides of the same.

In testimony that I claim the invention

set forth above I have hereunto set my hand this 20th day of July, 1920.

DAVID ZAIDEN.
